(57) **CLAIM**

The ornamental design for a motorcycle derby cover, as shown and described.

DESCRIPTION

FIG. 1 is a left side view of the motorcycle derby cover embodying the present invention while in use.

FIG. 2 is an enlarged left side view of the design shown in FIG. 1; and,

FIG. 3 is an enlarged perspective view of the design shown in FIG. 1.

The present application is directed to the design illustrated in the drawings. The other features of the drawings, such as the motorcycle shown in FIG. 1, are not considered part of the design sought to be patented, and have accordingly been shown in broken lines.

The broken lines which define the boundaries of the claimed design form no part thereof.

The design sought to be patented is not visible in the top, bottom, front, and rear views. Accordingly, these views have been omitted.

The right side view of the design is not visible in its normal or intended use because it is substantially obscured by the motorcycle transmission. Therefore, the right side view is not a matter of ornamental concern, and has been omitted from the drawings.
